CLAIM

The ornamental design for an AR lower parts holding template, as shown and described.

DESCRIPTION

FIG. 1 is a perspective view of an AR lower parts holding template, showing my new design;

FIG. 2 is a top plan view thereof;

FIG. 3 is a bottom plan view thereof;

FIG. 4 is a left-side elevational view thereof, the right-side elevational view being a mirror image thereof; and,

FIG. 5 is a top plan view thereof, the bottom plan view being a mirror image thereof.

The broken lines in FIGS. 1 and 2 depict portions of the AR lower parts holding template that form no part of the claimed design.
